UNITED STATES PATENT OFFICE.

ALMERON E. CALKINS, OF ALLEGAN, MICHIGAN.

MOTOR.

No. 866,330.

Specification of Letters Patent.

Patented Sept. 17, 1907.

Application filed November 24, 1906. Serial No. 344,823.

To all whom it may concern:

Be it known that I, ALMERON E. CALKINS, a citizen of the United States, residing at Allegan, in the county of Allegan and State of Michigan, have invented certain new and useful Improvements in Motors; and I do hereby declare the following to be a full, clear, and exact description of the invention, such as will enable others skilled in the art to which it appertains to make and use the same.

10 My invention relates to new and useful improvements in motors and more particularly to that class adapted to be used for propelling boats, automobiles, air ships or the like and my object is to provide a motor of this class which will propel the article to which it is attached without employing the usual form of gearing or propellers.

A further object is to provide a motor of this class whereby the usual form of reciprocating piston head is dispensed with and the atmosphere and water utilized to form one end of the combustion chamber.

20 Other objects and advantages will be hereinafter referred to and more particularly pointed out in the claims.

In the accompanying drawings which are made a part of this application, Figure 1 is a sectional view through my improved form of motor and one end of a boat showing the motor applied to use thereon. Fig. 2 is a sectional view of a still further modified form of motor.

30 For convenience of illustration I have shown the motor applied to use upon a boat although it will be understood that it may be employed in connection with any form of vehicle requiring a motor to propel the same.

35 Referring to the drawings in which similar reference numerals designate corresponding parts throughout the several views, 1 indicates a boat which may be of the usual or any preferred form, in the rear end of which and adjacent the bottom thereof is disposed my improved form of motor, said motor comprising a hollow cylinder 2, which is opened at one end and provided at its opposite end with a head 3.

Any suitable form of packing may be employed for preventing leakage around the cylinder and in this instance I have provided the outer periphery of the cylinder with a flange 4, between which and the adjacent portion of the boat is interposed a packing 5 and by which means the water is prevented from entering the boat around the cylinder.

45 Disposed above the cylinder 2 and located at any suitable point in the boat is a tank 6 in which is adapted to be disposed any suitable combustible material such as vaporized gasoline, alcohol or like material and the tank is connected with the inner or closed end of the

cylinder by means of a feed pipe 7 at a point within 55 the length of which is disposed a valve 8 so that the combustible material may be shut off from the engine when desired.

Disposed within the cylinder 2 and at any suitable point, is a plug 9 with which is adapted to coöperate 60 a longitudinally movable pin 10, the pin and plug forming opposite poles of an electric circuit so that when the pin 10 is directed into engagement with the plug 9 and the circuit then broken, a spark will be formed which will ignite the gases within the engine, 65 the plug and pin being connected to any suitable source of electric current such as storage batteries 11, the plug 9, being connected to one pole of the batteries by means of a wire 12 while the opposite pole of the batteries is secured to a head 13 on the pin 10 by means 70 of a wire 14 so that when the pin is in engagement with the plug, the circuit through the batteries will be completed.

The pin 10 is disposed through a stuffing box 15 and is surrounded by a spring 16 which is disposed between 75 the stuffing box 15 and the head 13, the spring normally holding the pin 10 out of engagement with the plug 9.

It is my desire to employ any convenient device for successively directing the pin 10 into engagement with the plug 9 and for convenience of illustration I have 80 shown a cam 17 which is mounted upon a shaft 18, said shaft and cam being rotated in any suitable manner so that when the lip 19 of the cam is directed against the head 13 of the pin, said pin will be directed into engagement with the plug 9 and as soon as the lip has 85 passed by the head 13, the spring 16 will quickly remove the pin from engagement with the plug thereby causing a spark.

While I have shown the motor as disposed entirely below the water line I desire it to be understood that if 90 deemed advisable the closed end of the cylinder may be disposed above the water line in which event the combustion material will be directed into the upper end of the cylinder by any suitable means other than gravity. It will also be seen that if desired the motor 95 may be placed entirely outside of the boat by securing the same to the rear end thereof or other convenient point.

In Fig. 2 the interior of the cylinder 2 is provided with a circumferential shoulder 20 which is located 100 near the closed end of the cylinder and is provided upon one side with a tapered seat 21 with which is adapted to coöperate a conical valve 22 which is supported within the cylinder by means of a stem 23 extending through a suitable bearing in the head 3, the 105 outer end of the stem 23 having a head 24 thereon. In order to normally hold the valve 22 upon the seat 21 I dispose a spring 25 around the stem 23 and between the

- heads 3 and 24 and by this construction it will be seen that the charge of explosive material is retained within a chamber 26 at one end of the cylinder 2 and the water is prevented from entering said chamber by means of 5 the valve 22. By this construction it will be seen that when the explosion is made the valve 22 is moved longitudinally, thereby allowing the force of the explosion to pass through the cylinder 2 and against the volume of water and as soon as the force of the explosion is removed from the valve 22 the spring 25 will immediately return the valve to its seat thus excluding the water from the explosion chamber.
- It will thus be seen that I have provided a very cheap and economical motor for driving a boat or other vehicle 10 15 and one wherein the volume of water or atmosphere is employed for forming one end of the combustion chamber, the weight of the water or atmosphere serving to drive the boat or vehicle forward when the explosion is directed against the same and it will further be seen 20 that when the explosion occurs more or less of a vacuum will be formed in the cylinder thereby preventing a rapid entrance of the water and giving the explosive material time to enter the inner end of the cylinder.
- What I claim is:
- 25 1. In a motor for boats the combination with a boat having an opening in the stern thereof; of a cylindrical tube closed at one end and open at the other adapted to be disposed through said opening, a peripheral flange on said cylindrical tube adapted to prevent longitudinal movement of said tube, a gasket interposed between said

peripheral flange and the body of the boat, a feed tube for gas communicating with the closed end of said cylindrical tube, and means to intermittently cause a spark in said tube whereby the gas will be exploded.

2. In a motor for boats, the combination with a boat having an opening in the stern thereof; of a cylindrical tube closed at one end and open at the other adapted to be disposed through said opening, means to prevent longitudinal movement of the tube in said opening, a feed tube for gas communicating with the closed end of said cylindrical tube, and means to intermittently cause a spark in said tube, whereby the gas will be exploded.

3. The herein described motor, comprising a cylindrical tube open at one end and closed at the other, a peripheral flange on said cylindrical tube adapted to prevent longitudinal movement thereof, a shoulder near the closed end of said cylindrical tube, a valve adapted to be normally seated against said shoulder, a feed tube for gas connected to the rear end of the cylinder, and means to intermittently cause a spark in said rear end, whereby gas will be exploded.

4. The herein described motor, comprising a cylindrical tube adapted to be disposed in a boat below the water's surface, the said tube being open at one end and closed at the other, means adapted to prevent longitudinal movement of said tube, a gas chamber at the closed end of said tube, a feed tube for gas communicating with said rear end, and means to intermittently cause a spark in said rear end, whereby the gas will be exploded.

In testimony whereof I have signed my name to this 60 specification in the presence of two subscribing witnesses.

ALMERON E. CALKINS.
